(57) **CLAIM**

The ornamental design for a beam projector, as shown and described.

DESCRIPTION

FIG. 1 is a front left perspective view of a beam projector, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear right perspective view thereof;

FIG. 9 is another front left perspective view thereof showing a state of use in which a sensor on the top of the beam projector is protruded; and,

FIG. 10 another right-side view thereof showing a state of use in which a body of the beam projector is rotated in clockwise direction relative to FIG. 5.

The even-dash broken lines illustrating portions of the beam projector form no part of the claimed design.
